(57) **CLAIM**

The ornamental design for a sign, as shown and described.

DESCRIPTION

FIG. 1 is a perspective view of a sign made in accordance with the present invention;

FIG. 2 is a front view of the sign of FIG. 1;

FIG. 3 is a right side view of the sign of FIG. 1, the left side view being a mirror image thereof;

FIG. 4 is a top view of the sign of FIG. 1;

FIG. 5 is a bottom view of the sign of FIG. 1; and,

FIG. 6 is a rear view of the sign of FIG. 1.

The sign support stake shown in broken lines in the Figures is for illustrative purposes only and forms no part of the claimed design.
